Primary Examiner — Darlington Ly*Assistant Examiner* — Nasim Abdulaziz Ali(74) *Attorney, Agent, or Firm* — Studebaker & Brackett PC(57) **CLAIM**

The ornamental design for a side rail for a vehicle lid, as shown and described.

DESCRIPTION

FIG. 1 is a perspective view of a side rail for a vehicle lid embodying my new design,

FIG. 2 is a top plan view thereof,

FIG. 3 is a front elevation view thereof,

FIG. 4 is a rear elevation view thereof,

FIG. 5 is a right side elevation view thereof; and,

FIG. 6 is a left side elevation view thereof.

The broken lines in the drawings illustrate portions of the side rail for a vehicle lid that form no part of the claimed design.
